UNITED STATES PATENT OFFICE.

LESTER R. WELLMAN, OF CHICAGO, ILLINOIS, ASSIGNOR TO FRIEDELEY-VOSHARDT CO.,
OF CHICAGO, ILLINOIS, A CORPORATION OF ILLINOIS.

DESIGN FOR A LANTERN.

Application filed March 24, 1925. Serial No. 12,865. Term of patent 7 years.

To all whom it may concern:

Be it known that I, LESTER R. WELLMAN, design.
a citizen of the United States, residing at Chicago, in the county of Cook and State of Illinois, have invented a new, original, and ornamental Design for a Lantern, of which the following is a specification, reference being had to the accompanying drawing, forming part thereof.

Fig. 1 is a front elevation showing my new

Fig. 2 is a plan view showing my new design.

I claim—

The ornamental design for a lantern, as shown.

LESTER R. WELLMAN.
